UNITED STATES PATENT OFFICE.

THEODORE TRIEBEL, OF GLASTONBURY, CONNECTICUT.

DESIGN FOR A HANDLE FOR SPOONS AND FORKS.

SPECIFICATION forming part of Design No. 14,262, dated September 4, 1883.

Application filed June 7, 1883. Term of patent 7 years.

To all whom it may concern:

Be it known that I, THEODORE TRIEBEL, of Glastonbury, in the county of Hartford and State of Connecticut, have invented a certain new and original Design for Handles for Forks, Spoons, Ladles, &c., of which the following is a specification, reference being had to the accompanying drawings, forming part thereof, and to the letters of reference marked thereon.

10 The leading features in my new design consist in the outline of the top and sides of the handle, and in the scroll at the tip and the double flower-pot and ornamental stand shown both on the front and back of the handle, and 15 extending beyond the sides or edges of the same.

Figure 1 shows the front, and Fig. 2 the back, side of the spoon.

A is the tip of the handle, and the form shown 20 in the drawings is in itself a description. B is the double flower-pot and ornamental stand,

extending beyond the tapering edges of the handle, and also shown in relief on both its sides. C is the scroll upon the inside of or front of the tip of the handle. Thus the general form 25 and appearance of the several parts of my new design are shown in the accompanying drawings.

What I claim as my invention is—

The design for a fork or spoon handle, herein shown and described, consisting of the outline of the top and sides of the handle and the scroll at the tip, and the double flower-pot and a representation of a calla lily growing from the pot on each side of the handle and the double ornamental stand or base, substantially as 30 set forth.

THEODORE TRIEBEL.
